CONTROLLING DEVICE FOR AIR
CONDITIONING SYSTEMS

Arthur C. Booth, North Ferrisburg, Vt.

Application February 14, 1945, Serial No. 577,854

1 Claim. (Cl. 200—52)

This invention relates to air conditioning systems and more particularly a device for controlling the operation of the same.

One of the objects of this invention resides in the provision of means whereby air conditioning systems can be controlled in accordance with the degree of humidity within that area of a room or building having the system installed therein.

Another object of this invention resides in the provision of means whereby operation of air conditioning systems can be regulated to meet predetermined temperature conditions within rooms and building provided with such systems.

A further object of this invention resides in the provision of means for controlling the electrical systems of air conditioning systems in accordance with predetermined degrees of humidity within rooms or building provided with air conditioning systems.

A still further object of this invention resides in the provision of means whereby the exact temperature of rooms or building can be maintained subsequent to adjusting the means for operation under the influence of a predetermined degree of humidity with a room or building.

Aside from the aforesaid objects, this invention resides in the provision of means adapted to be operated under the wet and dry bulb thermometer principle in controlling air conditioning systems of rooms and building.

In addition to the foregoing objects, this invention resides in the particular manner of setting the device for controlling air conditioning systems.

With these and other objects in view, this invention resides in certain novel features of construction and arrangement of elements to be hereinafter more particularly set forth in the specification, illustrated in the accompanying drawings and pointed out in the appended claim and, although this disclosure depicts my present conception of the invention, the right is reserved to resort to such changes in construction and arrangement of elements as come within the spirit of the invention.

In the accompanying drawings forming a part of this application:

Fig. 1 is a side view of the controlling device.

Fig. 2 is a longitudinal vertical sectional view therethrough.

Fig. 3 is an enlarged vertical sectional view through the neck of the cylinder and connection thereof to the mercury tube.

Fig. 4 is an enlarged sectional view through a portion of the cylinder.

Fig. 5 is a horizontal sectional view through the cylinder taken approximately on line 5—5 of Fig. 2.

Fig. 6 is an enlarged vertical sectional view through the lower portion of the contact plunger.

In the present illustration of this invention, the numeral 5 designates, in general, a device for controlling the operation of air conditioning systems in accordance with predetermined degrees of humidity to be had in rooms and buildings and, in the instant disclosure, the same is mounted on a wall W but may be supported by any suitable element where it may be electrically connected to the electric system of the air conditioning system which it is to control.

The device 5 consists of an elongated cylinder 6 having a neck 7 at its lower end and sealed at its upper end by a removable cap 8 which is provided with an upstanding boss 9 having a bore 10 therein and a packing gland 11 adapted to retain a packing 12 preferably of a graphite base so as to frictionally support an electric contact plunger 13 axially within the cylinder for perpendicular movement therein.

Connected to the lower portion of the neck of the cylinder in airtight relation thereto as by a sleeve 14 is a substantially U-shape tube 15 within which is retained a predetermined volume of mercury indicated by the numeral 16.

The aforesaid contact plunger 13 extends outwardly beyond the packing gland 11 into engagement with a rocker arm 17 having its free end 18 constructed in the form of a pointer to operate in conjunction with an adjustable indicating scale 19 attached to the wall W or other suitable place adjacent the pointer.

Engaging the rocker arm 17 on that side thereof opposite the side engaged by the aforesaid contact plunger is an expansion thermostat 20 adapted to be actuated by the temperature within a room or building wherein the air conditioning system is installed.

Disposed on the contact plunger and bearing at its inner end against the packing gland is an expansion coil spring 21 and, in order to regulate the force of the thermostat 20 against the contact plunger as by the rocker arm 17, an adjustable control nut 22 is threadedly disposed on the contact plunger and bears against the outer end of the spring. Through the instrumentality of the aforesaid association of elements it will be noted that, when said control nut has been changed from a previously set position and the

pressure balance along the rocker arm has been disrupted, an immediate change in the controller will prevail. This change being caused by the humidity in the room or building and the contact system will be sensitive to the same when equilibrium has been established by the device.

Secured to and insulated from the contact plunger, at its inner end, is a conductor rod 23 which extends axially into the neck of the cylinder for contact with the mercury within the tube 15 to make electrical connection between a terminal 24 carried by the sleeve and projecting into the mercury and an electrical terminal 25 carried by the cylinder cap and contacting said conductor rod 23 at all times by a tension arm 26 carried thereby. Said electrical terminal 25 is herein disclosed as being in the form of an elongated rod threaded secured and sealed to the cylinder cap to prevent escape of nitrogen injected into the cylinder through the instrumentality of a valved conduit 27 connected to the cap or any other desired portion of the cylinder.

Removably threaded into the sleeve 14 is a filling plug 28 to permit injection of the mercury into the tube 15.

Disposed against the outer periphery of the cylinder 8 is a wick 29 adapted to retain moisture at a low temperature from a cistern or the like, not shown, in order that the nitrogen within the cylinder will remain cool and not expand until the humidity within the room increases.

Extending from the terminals 24 and 25 are electric wires 30 and 31 which have their opposite ends connected to the electric power system of the air conditioning system, not shown, so as to control the same by the controlling device forming the subject matter of this application.

With the aforesaid device connected to the electric system of an air conditioning system the thermostat 20 acts as a dry bulb thermometer forcing the plunger 18 into proper contact position at varying temperatures. When said plunger is in exact position for a certain room or building temperature, the nitrogen in the cylinder 8 is retained in inactive condition within the cylinder by the cooling effect of the wick fed by a cistern of water or other similar means. The evaporating water causes a cooling effect and thereby reduces the temperature of the nitrogen. When the moisture content in the air is below the set relative humidity and under range is experienced between the two thermometer elements causing a reduction in pressure the mercury is permitted to level off until it forms an equilibrium pressure, or comes in contact with contact rod 23, whereupon, the air conditioning system is started and thus discharges or throws moisture into the surrounding atmosphere. With more moisture per cubic foot, the relative humidity will be increased

until the thermometer differential has been sufficiently reduced at which point the cooling effect or evaporation rate has been reduced on the surface of the cylinder. With the nitrogen in cylinder 8 at a higher degree in temperature, greater expansion occurs and forces the mercury back into the tube 15 and away from the contact 24 thus breaking the circuit between said contact and contact rod 23 and thereby automatically rendering the air conditioning system inoperative until the aforesaid circuit is again closed as aforesaid.

With this invention fully described, it is manifest that means are provided whereby air conditioning systems can be precision regulated in accordance with predetermined degrees of humidity and, through the simplicity of the embodiment set forth, wear is reduced to the minimum and the cost of manufacture sufficiently low to meet public acceptance.

Having thus described my invention what I claim and desire to protect by Letters Patent is:

A device for controlling the operation of an air conditioning system operated by electrical power comprising, a cylinder having one end open and a neck formed on its opposite end, a cap removably sealed on the open end of the cylinder, a boss having a bore therein carried by said cap and extending axially therefrom, a contact plunger slidably extending through the bore of said boss, a packing gland in the boss and surrounding the contact plunger, an expansion coil spring surrounding the contact plunger and resting on the packing gland, an adjustable nut on the contact plunger and engaging the outer end of said spring, a rocker arm engaging the free outer end of the contact plunger and having its free end formed into a pointer, an adjustable scale disposed adjacent the pointer end of the rock arm, a thermostat engaging the rocker arm adjacent the free end thereof, a substantially U-shape tube containing mercury, a sleeve connecting and sealing one end of the tube to the outer end of the neck of the cylinder, a contact secured to the sleeve and extending therein, a contact rod electrically connected to the inner end of the contact plunger and extending therefrom toward the mercury within the tube, a conductor rod secured to the cap and extending within the cylinder, a contact arm carried by said conductor rod and yieldingly bearing against the aforesaid contact rod carried by the contact plunger, a filling plug in the sleeve for the mercury, a filling conduit including a valve in the cap for injecting nitrogen into the cylinder, and a moisture retaining wick surrounding the cylinder to cool the nitrogen within the same.

ARTHUR C. BOOTH.
